UNITED STATES PATENT OFFICE.

THOMAS P. HARRIS, OF CLARINDA, IOWA.

RADIATOR-PROTECTOR.

1,386,174.

Specification of Letters Patent. Patented Aug. 2, 1921.

Application filed January 28, 1919. Serial No. 273,684.

To all whom it may concern:

Be it known that I, THOMAS P. HARRIS, a citizen of the United States, and resident of Clarinda, in the county of Page and State of Iowa, have invented a certain new and useful Radiator-Protector, of which the following is a specification.

The object of my invention is to provide a radiator protector of simple, durable and inexpensive construction, adapted to be mounted on the front of a radiator and to be used for controlling the passage of air through the radiator.

More particularly it is my object to provide such a device made in two parts adjustably connected together, so that one set of fastening devices may be used for connecting the entire protector with the radiator and thereafter the adjustment may be made for moving the movable portion of the protector to any position of its movement.

A further object is to provide such a protector preferably made of such material that the protector members may be made of maximum size and one of them may be provided with indicating lines and characters for showing where the ends of the protector members should be cut off to reduce the size of such members for use with automobiles of various makes.

Still a further object is to provide such a structure including two protector members of substantially the same size and shape, adapted to be superposed one upon the other.

With these and other objects in view, my invention consists in the construction, arrangement and combination of the various parts of the device, whereby the objects contemplated are attained, as hereinafter more fully set forth, pointed out in my claim, and illustrated in the accompanying drawings, in which:

Figure 1 shows a front elevation of the outer and upper member of my radiator protector.

Fig. 2 shows a front elevation of the lower inner member thereof.

Fig. 3 shows a side elevation of a radiator with my improved protector mounted thereon in its extended position.

Fig. 4 shows a front elevation of one member of one of the fastening devices, and

Fig. 5 shows a side elevation of one of the complete fastening devices.

It is my purpose to make a radiator pro-

tector of very simple and inexpensive material, such, for instance, as stiff cardboard, which protector preferably has two members indicated in the accompanying drawings by 60 the reference characters 10 and 11. These members are preferably of the same size and shape and outline, so that the member 11 may be superposed on the member 10.

When installed on the radiator the protector members have a horizontal bottom edge, vertical side edges and an upper edge curved from its central point downwardly and outwardly, as illustrated in Figs. 1 and 2.

It will be understood that any suitable material can be used, but I preferably use some materials on which an advertisement may be printed or stamped.

The lower protector member 11 is provided with spaced, vertically elongated slots 14. There is preferably provided a notch 15 in the central part of the lower edge of the member 11.

For fastening the two protector members 80 together and fastening both to the radiator, various suitable devices might be employed. As shown in the drawings, I use a metal plate or disk 16, having two spaced, elongated, parallel slots 17. I extend through the slots 85 17, the ends of a flexible metal tie 18.

In the assembling of the protector and the installation thereof on the radiator, the member 11 is superposed on the member 10 with the holes 12 in registration with the 90 slots 17. The ends of the tie device 18 are extended through the slots 14, and then through the holes 12. Said ends are then extended through the radiator 19 and are bent or tied as at 20 in Fig. 3.

The parts may be tied or fastened tightly enough to that there is frictional engagement between the members 10 and 11, and so that the member 11 will stay in any raised position in which it may be put.

Thus it is possible, when it is desired to allow some air to pass through the radiator, to leave the member 11 in its lowered position where it is directly in front of the member 10. The member 11 may be raised to a variety of positions so that it may leave any desired size opening above the member 10 for air to pass through the radiator.

In Fig. 3 I have shown the member 11 raised to its upper position of movement 110 for closing the entire front end of the radiator and preventing the passage of air there-

through. The device would be in this position when stopped in very cold weather. The member 11 could be lowered slightly if it was desired to let some air through the 5 radiator, and could then be raised when the machine is stopped, for retaining the heat under the hood.

I preferably, in manufacturing for the market, make the members 10 and 11 of a 10 maximum size. It is then possible to use the same members for a considerable variety of makes of cars. The protectors are sold in the maximum size, and the member 11 is provided near its side edges with a series 15 of vertical lines 21, adjacent to which are indicating characters 22 for indicating the lines on which the ends of the protector members should be cut for reducing the protector members from their maximum size 20 to a smaller size to fit certain cars. The device is preferably made of the size to fit the largest car on which it is likely to be used, and the lines or indicating characters show where the members should be cut for 25 fitting them for use with smaller cars. The lines 21 are scored, but the scoring may be dispensed with.

It will be seen that the entire device is of very simple and inexpensive construction, 30 and yet affords an efficient and quickly adjusted air control device for the front of the radiator.

Some changes may be made in the con-

struction and arrangement of the parts of my improved radiator protector without departing from the essential purposes and features of my invention, and it is my intention to cover by my claim any modified forms of structure or use of mechanical equivalents which may be reasonably included 40 within its scope.

I claim as my invention:

In a radiator protector, the combination of two protector members, one capable of sliding movement relative to the other, and 45 designed to be placed against the front of a radiator, one of said protector members being provided with openings and the other being provided with vertical slots, and a means for securing both of said members 50 to a radiator and at the same time permitting an adjustment of one of the members relative to the other, said means comprising fastening devices extended through said openings and through said slots, and designed to be extended through the radiator, 55 and being provided with means on their rear ends for engaging the rear surface of the radiator to frictionally hold the protector members in any adjusted position relative to each other and in position against the front of the radiator, for the purposes stated.

Des Moines, Iowa, January 8, 1919.

THOMAS P. HARRIS.
